E. H. WOELFFEL.
CORNERS BRACKET FOR BED SPRINGS.
APPLICATION FILED APR. 23, 1914.
1,104,336.

Patented July 21, 1914.

UNITED STATES PATENT OFFICE

ERNEST H. WOELFFEL, OF POINT PLEASANT, WEST VIRGINIA, ASSIGNOR TO WEST VIRGINIA MALLEABLE IRON CO., OF POINT PLEASANT, WEST VIRGINIA.

CORNER-BRACKET FOR BED-SPRINGS.

1,104,336.

Specification of Letters Patent.

Patented July 21, 1914.

Application filed April 23, 1914. Serial No. 833,966.

To all whom it may concern:

Be it known that I, ERNEST H. WOELFFEL, a citizen of the United States, residing at Point Pleasant, in the county of Mason and 5 State of West Virginia, have invented a new and useful Corner-Bracket for Bed-Springs, of which the following is a specification.

This invention relates to new and useful 10 improvements in bed springs and more particularly to a corner casting or bracket for receiving the ends of the side rails.

The primary object of the invention is the provision of a device of this character 15 whereby the springs may be adjusted or tightened after the side rails are placed in the sockets of the casting or bracket.

A further object is the provision of means 20 for using the side rails now in ordinary use.

With the foregoing and other objects in 25 view which will appear as the description proceeds, the invention resides in the combination and arrangement of parts and in the details of construction hereinafter described and claimed, it being understood that 30 changes in the precise embodiment of the invention herein disclosed can be made within the scope of what is claimed without departing from the spirit of the invention.

In the drawings:—Figure 1 is a plan 35 view. Fig. 2 is a side view. Fig. 3 is a longitudinal sectional view showing the side rail being placed in the socket. Fig. 4 is a longitudinal sectional view showing the parts assembled. Fig. 5 is a detail of the plug for the end of the side rail.

In the drawings the numeral 1 indicates 40 a bracket on the lower end of which is formed an integral socket 2 and on the top end of which is secured the angle iron end piece 3 of the spring frame to which is secured the spring fabric 4. The socket 2 is formed with opening 5 and the end of a sleeve 6 having the interiorly threaded extension 7 is received in the socket and the 45 extension 7 passes through the opening 5.

The numeral 8 indicates a side rail of the 50 ordinary construction used in the frame work of the bed spring, and a plug 9 is inserted in the end of the rail. The end of the side rail is adapted to be received in the

sleeve 6 and a screw 10 is threaded in the end of the sleeve and engages the plug in the end of the side rail.

In manufacturing bed springs considerable trouble is encountered in tightening the 55 springs or the wire fabric after the side rails have been inserted in the bracket. It will be seen that one end of each side rail will be placed in one corner bracket and it is then necessary to separate the brackets or 60 increase the distance therebetween to insert the opposite end of the side rail. After the wire has been so stretched it is with great difficulty that it is finally tightened sufficiently to sustain the necessary weight. It 65 will be noted that in the ordinary construction of spring it is necessary to stretch the springs or fabric the same distance as the length of the socket member and it is therefore impossible in the ordinary construction 70 to tighten the springs for a greater length.

Applicant has overcome the above objection by providing the sleeve which is adapted to enter the socket in the bracket and also to receive the end of the side rail. 75 The sleeve may be of any desired length and in assembling the parts the sleeve is applied over the end of the side rail and by inserting the same in the socket the wire is stretched only to such an extent as the length 80 of the socket member. It will thus be seen that by having the sleeve of greater length than the socket member an adjustment of greater length can be secured for tightening the fabric or spring. After inserting the 85 sleeve in the socket the adjustment or tightening is secured by turning the screw 10 which engages the plug in the end of the side rail.

Having thus described the invention what 90 I claim as new and desire to secure by Letters Patent is:—

1. The combination with the side rail of a bed spring, of a bracket having an integral socket, a sleeve received in the socket 95 and adapted to receive the end of the side rail, and an adjusting screw passing through the end of the sleeve and engaging the end of the side rail.

2. The combination with a hollow side rail 100

of a bed spring, of a plug inserted in the end of the rail, a bracket having an integral socket, a sleeve received in the socket and adapted to receive the end of the rail, and an 5 adjusting screw passing through the socket and sleeve and engaging the plug in the side rail.

In testimony that I claim the foregoing as my own, I have hereto affixed my signature in the presence of two witnesses.

ERNEST H. WOELFFEL.

Witnesses:

SELINA WILLSON,
I. E. SIMPSON.
